UNITED STATES PATENT OFFICE.

AUGUST STEINER, OF HOMEWOOD, ILLINOIS.

CORN-HARVESTING MACHINE.

SPECIFICATION forming part of Letters Patent No. 656,675, dated August 28, 1900.

Application filed February 28, 1900. Serial No. 6,781. (No model.)

To all whom it may concern:

Be it known that I, AUGUST STEINER, a citizen of the United States, residing at Homewood, in the county of Cook and State of Illinois, have invented a new and useful Corn-Harvesting Machine, of which the following is a specification.

This invention relates to corn-harvesting machines, and is designed as an improvement 10 on the constructions set forth and claimed in my Patents No. 436,386, dated September 16, 1890, and No. 606,824, dated July 5, 1898.

The object of the invention is to simplify 15 and improve the construction and operation of machines of this class and to render the same more efficient in operation.

The invention consists substantially in the construction, combination, location, and arrangement, all as will be more fully herein- 20 after set forth, as shown in the accompanying drawings, and finally pointed out in the appended claims.

Referring to the accompanying drawings and to the various views and reference-signs 25 appearing thereon, Figure 1 is a broken view in plan, parts in horizontal section, showing a construction embodying the principles of my invention. Fig. 2 is a side elevation, parts in vertical section. Fig. 3 is a broken 30 view, in vertical section, on the line 33, Fig. 1, looking in the direction of the arrows. Fig. 4 is a broken detail view in perspective of the universal shaft-coupling employed in connection with my invention. Fig. 5 is a 35 detail view, in vertical section, on the line 55, Fig. 1, looking in the direction of the arrows. Fig. 6 is a similar view on the line 66, Fig. 3, looking in the direction of the arrows. Fig. 7 is a detached detail view in section showing 40 the manner of adjusting the snapping-frame. Fig. 8 is a similar view in perspective of the snapping-frame adjusting-block. Fig. 9 is a broken detail view in section showing the manner of hinging the snapping- 45 frame for vertical adjustment. Fig. 10 is a detail view of the snapping-rolls, showing the snapping-rib. Fig. 11 is a broken detail view in plan showing the wiper for preventing choking up of the snapper-rolls.

50 The same part is designated by the same reference-sign wherever it occurs throughout the several views.

Reference-sign A designates the main frame of the machine, in which is journaled the main shaft B. Upon this shaft are mounted 55 the traction or master wheels C, which support the machine and through the rotation of which motion is imparted to the various operative parts of the apparatus.

Reference-sign D designates what I shall term the "snapping-frame," and in this frame are journaled the snapping-rolls E F, presently to be more fully described and explained, and also the gathering and detached ear-conveying devices. The snapping-frame 60 D is suitably sleeved at its rear end for rocking movement about a shaft G, which shaft is journaled in the main frame, as clearly shown in Fig. 9. The journal-bearing of shaft G in the main frame is provided with 65 a hub (indicated at H) upon which is sleeved the side bar of the snapping-frame D, and at its front end the snapping-frame is supported by an angle-block J, suitably bolted or otherwise secured to an angle-plate K of the snapping-frame. The angle-block J is provided 70 with a threaded aperture adapted to receive a screw-rod L therethrough. This screw-rod bears upon a convenient part of the main frame A, as indicated in Fig. 7. By this construction the snapping-frame may be rocked 75 about the axis of shaft G by turning screw-rod L. In order to efficiently guide the swinging movement of snapping-frame D, the main frame A may be provided with a 80 plate M, arranged to engage a slot N in angle-block J. (See Fig. 8.)

At the front end of the snapping-frame are pivotally supported the gathering-frames O P, arranged to project forwardly therefrom. 90 The frame O is journaled to rock upon a shaft Q, suitably journaled in the front end of the snapping-frame, and the gathering-frame P is journaled to rock upon pivot-studs R R, suitably mounted in snapping-frame D. To 95 each of the gathering-frames O P is connected a suitable cord or other connection S T, operated in any suitable manner, as from a shaft V, having a crank arm or handle W, and by means of which the gathering-frames may be 100 rocked or swung about their pivots upon the snapping-frame, so as to raise and lower the front ends of said gathering-frames. Each gathering-frame is provided with a hood or

cover 'A', which serves to inclose the gathering devices carried by said frames and to prevent clogging of the same. The gathering-frames project forwardly from the front end 5 of the snapping-frame on slightly-diverging lines, and at their extreme forward ends said frames diverge more acutely, as clearly indicated in Fig. 1.

Upon the shaft Q, about the axis of which 10 the gathering frame O is mounted to rock, is mounted a sprocket-gear B', (see Figs. 3 and 6,) which sprocket-gear and a coöperating sprocket-gear C' on shaft G are engaged by a belt D', by which rotation is imparted to a 15 bevel-gear E' on shaft Q. This gear engages and drives a gear F', carried by a shaft G'. Upon shaft G' are mounted the drive-sprockets H' J', through which the upper and lower gathering-chains K' L' are driven. The upper 20 chain K' is engaged over suitable guide-sprockets M' N', so arranged as to cause one leg or run of the gathering-chain to extend longitudinally of the gathering-frame O and to project from the inner side thereof into the 25 space between the frames O and P, as clearly shown in Fig. 1. Similarly, upper and lower gathering-chains O' P' are provided upon gathering-frame P, said chains engaging over suitable guide-sprockets Q' R' and driven from 30 sprockets S' T', carried by a shaft V'. The shaft V' is driven from a shaft W' through a universal joint, (indicated generally at A²,) as shown in Fig. 4. This universal coupling in the particular form shown comprises cross- 35 arms B² C², respectively connected to shafts V' W' and arranged in right-angular relation with respect to each other and each engaging at the ends thereof with pins or projections of a ring D², as clearly shown. By this construction the shaft V' may be readily driven 40 from shaft W' and at the same time will be permitted swinging movement relative thereto, as in swinging the frame P, about its hinge-joints. The shaft W' is driven through 45 a sprocket-wheel E², which is engaged by a sprocket-chain F², operating over a sprocket-gear driven by shaft G. The gathering-chains K' L' O' P' are provided with projecting pins or teeth G², which project therefrom and into 50 the space between the frames O P and serve to engage the stalks of corn as the machine proceeds through the field, thereby carrying or delivering the same to the action of the snapping-rolls, as will presently be more fully 55 explained, and, similarly, the chain F² is provided with projecting pins or paddles H², which serve to convey the detached ear from the snapping-rolls.

The snapping-rolls E F extend longitudinally of the snapping-frame and are suitably journaled in bearings formed in said frame. These rolls are corrugated, the corrugations being respectively right and left handed, as clearly shown, and said rolls are driven in 65 opposite directions through intermeshing gears J², one of said rolls being positively driven through a shaft K² from shaft G.

It sometimes occurs that the snapping-rolls fail to effect a detachment of the ear of corn from the stalk. In order to insure a snapping of the ear from the stalk, I provide each of the rolls E F with a rib or projection L², the ribs or projections L² being spirally arranged on their respective rolls and of greater pitch than the corrugations of said rolls. As 75 clearly shown in the drawings, these ribs extend longitudinally of the rolls and in the reverse direction with respect to the corrugations of said rolls, and the individual ribs are arranged at such an angle that a pair of the 80 ribs converge toward each other in the direction of the center of the machine. By this means the ribs not only insure a detachment of the ears from the stalks, but even after the stalks are broken from the ears grip such 85 stalks tightly and draw them down between the rolls out of the way, the detached ears in the meantime, being too large to pass through the space between the rolls, either ride along such rolls or jump off at the side onto the 90 conveyer.

It sometimes occurs that a stalk or detached ear becomes lodged at the point of entrance into the space between the front ends of the snapping-rolls, thereby clogging up this entrance and arresting the proper action of the machine. In order to prevent this, I provide a wiper L³, suitably pivoted upon a convenient part of the frame adjacent to the front ends of the snapping-rolls. To this wiper is 100 connected a rod M³. The other end of this rod M³ is connected to a pivoted lever N², adapted to be rocked by means of a hand-lever or other suitable device (indicated at O²) arranged to extend into convenient position to be manipulated by the driver. From 105 this it will be seen that in case a stalk or ear of corn should lodge at a point adjacent to the front end of the snapping-rolls the driver may be able to readily free the obstruction 110 by operating the wiper without arresting the operation of the machine.

It will be observed and as above explained that the gathering-frames O P extend forwardly from the front end of the snapping-frame and that said frames are pivotally mounted independently of each other at the front end of the snapping-frame. At the extreme front end of said gathering-frames is provided a shoe p², adapted when necessary to rest upon the ground. Preferably the frames O P are tapering toward their front end, and they diverge from each other slightly during a greater portion of their length; but at their extreme end they are 125 provided with a wide divergence, so as to provide sufficient space for the ready entrance of the stalks of corn therebetween. It sometimes occurs, and especially where the corn has been standing in the field for some 130 time after its maturity, and hence has become brittle, that when the gathering-frames strike the stalk it will break and fall down before the gathering-chains can engage it. By pro-

viding the wide space at the front extremities of the gathering-frames and by the provision of sloping and tapering sides to the frame at this point instead of the machine 5 breaking and causing the stalks to fall down the stalks will be guided without breaking up to the point in the length of the gathering-frames where they will be engaged by the gathering-chains, and I arrange the upper 10 gathering-chains O' K' to extend as near to the front end of the gathering-frames as possible. In the particular form shown these upper gathering-chains extend to a point in the length of the gathering-frames 15 where the wide divergence thereof at their front extremities begins, and hence the danger of breaking down the stalks of corn by the engagement therewith of the gathering-frames is avoided. By hinging the gathering-frames at their rear ends said frames 20 may be set or raised or lowered to accommodate any desired condition of the corn. For instance, in cases where the corn has been blown down or bent over toward the ground 25 by the wind, the weight of the ears of corn, or otherwise, then the gathering-frames may be rocked so as to lower the extreme front ends thereof into contact with the ground, and hence when the machine proceeds along the 30 row of bent or blown-down corn each stalk will be picked up from the ground and sliding up the incline or sloping ends of the gathering-frames will be engaged by the gathering-chains, and thereby presented to the action 35 of the snapping-rolls. On the other hand, where the corn in the field is in an upright condition, then the front ends of the gathering-frames may be elevated above the ground, and hence will not be required to incur 40 the danger of having to plow through the ground in rough or uneven places.

It will be understood that the gathering-chains carry the stalk into the space between the front ends of the snapping-rolls. These 45 rolls, rotating constantly and in opposite directions with respect to each other, quickly feed the stalk through said rolls, and when the ear is reached said ear is detached from the stalk, the detached ear being delivered 50 into position to be carried away by the delivery-chain F². In many cases in a field of corn the ears are near the top of the stalks, while in many other cases in a field of corn the ear occurs lower down upon the stalks. 55 By hinging the snapping-frame at its rear end concentric with the shaft G and by supporting said frame at its front end by adjusting screw L it will be readily seen that the snapping-frame may be adjusted by raising 60 or lowering the same, so as to set the snapping-rolls at any desired height to suit the particular field or condition of the corn with reference to the height or the general height of the ears. Thus where the stalks are tall 65 and the ears occur at a considerable height from the ground the front end of the snapping-frame may be raised, so that the stalks

will be engaged by the snapping-rolls at a point just below the height of the ears. This adjustment relieves the snapping-rolls of considerable unnecessary wear by their engagement of the stalk at a point close to the ears, and hence enables the machine to move more easily and smoothly and with less power than if the stalk was engaged at a point nearer to the ground and was required to run through the rolls its entire length before the ear was reached. On the other hand, in case of exceedingly-low corn or short stalks, the front end of the snapping-frame may be lowered. 75 Thus the snapping-frame may be adjusted readily and easily to accommodate different conditions of length of stalk or height of the corn, and it will be understood that, independently of this adjustment of the snapping-frame, the gathering-frames may be tipped or adjusted about their pivots. It will also be seen that by hinging the snapping-frame at its rear end upon shaft G the weight of the parts supported by this frame is more evenly 80 distributed, and hence enables the machine to run more easily and with a minimum amount of power.

By the improvements above set forth I have greatly simplified and improved the construction of machines of this class, rendering the same more readily and easily adjusted to meet the conditions and requirements of different kinds of corn, so as to relieve the machine of unnecessary wear, thereby enabling it to run smoother and with the smallest amount of power, and I have produced by the details above described and set forth an exceedingly-efficient and easily operated and driven machine which is thoroughly practical and efficient in operation for the purposes for which it is intended. It is to be understood that in operation the machine is driven through the field of corn longitudinally of the rows, the gathering-frames extending 95 forwardly or in the direction of the length of the row and of the travel of the machine, so that the stalks of corn standing in the row will successively enter the space therebetween, thereby enabling the gathering-chains 100 to engage the stalks successively and properly present the same to the action of the snapping-rolls. These rolls feed the stalks therebetween and detach the ears therefrom as the machine advances through the field, 105 leaving the stalk standing and delivering the detached ear in any suitable manner, the various working parts of the machine receiving motion from the traction-wheels C.

Having now set forth the object and nature 110 of my invention and the various details of construction thereof and having described such construction, its purpose, function, and mode of operation, what I claim as new and useful and of my own invention, and desire 115 to secure by Letters Patent of the United States, is—

1. In a corn-harvesting machine, a main frame, an axle journaled therein and carry-

- ing traction-wheels, a snapping-frame, ear-detaching devices carried thereby, said frame being hinged at its rear end upon said main frame and independently of the axle, means 5 for adjustably supporting the front end of said snapping-frame, in combination with gathering devices pivotally supported upon such snapping-frame, as and for the purpose set forth.
10. 2. In a corn-harvesting machine, a main frame, an axle journaled therein and carrying traction-wheels, a snapping-frame, ear-detaching devices carried thereby, said snapping-frame being pivotally mounted at its 15 rear end upon said main frame and independently of said axle, an adjusting-block connected to the front end of said snapping-frame, an adjusting-screw for raising and lowering said adjusting-block, in combination 20 with gathering devices pivotally supported upon said snapping-frame, as and for the purpose set forth.
3. In a corn-harvesting machine, a main frame, an axle journaled therein and carrying traction-wheels, a snapping-frame, ear-detaching devices carried thereby, said frame being pivotally connected at its rear end to said main frame and independently of said axle, an adjusting-block connected to said 25 snapping-frame at the front end thereof, an adjusting-screw arranged to engage said block, whereby said snapping-frame may be raised and lowered, a guiding-plate connected to said main frame and engaging said adjusting-block to guide the same, in combination 30 with gathering devices pivotally supported upon said snapping-frame, as and for the purpose set forth.
4. In a corn-harvesting machine, a main frame, a traction-wheel mounted therein, an axle for said wheel, a driving-shaft journaled 40 in said main frame to the rear of said traction-wheel axle and arranged to be driven therefrom, a snapping-frame journaled upon said driving-shaft and carrying ear-detaching devices, means for adjustably supporting 45 said snapping-frame at a point in front of said traction-wheel, in combination with gathering devices pivotally supported upon said snapping-frame, as and for the purpose set forth.
5. In a corn-harvesting machine, a main frame, a traction-wheel journaled therein, an axle for said wheel, a driving-shaft journaled 50 in said main frame parallel with and to the rear of said traction-wheel axle and arranged to be driven therefrom, a snapping-frame sleeved upon said driving-shaft and carrying ear-detaching devices, an adjusting-block connected 55 to said snapping-frame at the front end thereof and in advance of said traction-wheel, an adjusting-screw engaging said block for raising and lowering said frame about its pivotal axis, in combination with gathering 60 devices pivotally supported upon said snapping-frame, as and for the purpose set forth.
6. In a corn-harvesting machine, a snap- 65
- ping-frame carrying snapping-rolls, said frame being pivotally mounted at its rear end, and means for vertically adjusting the front end thereof in combination with gathering-frames pivotally mounted upon horizontal axes at the front end of said snapping-frame, said gathering-frames extending forwardly from said snapping-frame, gathering devices 70 carried by said gathering-frames, connections for said gathering-frames, and means for actuating said connections for swinging said gathering-frames about their pivotal axes, as and for the purpose set forth. 75
7. In a corn-harvesting machine, a snapping-frame, ear-detaching devices carried thereby, said frame being pivotally mounted at its rear end, and means for vertically adjusting the front end thereof, gathering-frames pivotally mounted at their rear ends upon the front end of said snapping-frame, said gathering-frames extending forwardly from the front end of said snapping-frame, and means for rocking said gathering-frames 80 to raise and lower the front ends thereof, as and for the purpose set forth. 85
8. In a corn-harvesting machine, a snapping-frame, said frame being pivotally mounted at its rear end, and means for vertically adjusting the front end thereof, gathering-frames independently pivoted at their rear ends upon the front end of said snapping-frame, connections connected to each of said gathering-frames, and an operating-shaft to 90 which said connections are connected, whereby said gathering-frames may be rocked about their pivots, as and for the purpose set forth. 95
9. In a corn-harvesting machine, a snapping-frame, said frame being pivotally mounted at its rear end, and means for vertically adjusting the front end thereof, gathering-frames pivotally mounted on said snapping-frame at the front end thereof and extending forwardly therefrom, said gathering-frames 100 being arranged in parallel relation and slightly diverging from each other throughout the greater portion of their length, and widely diverging from each other at their front extremities, and gathering devices carried by said gathering-frames, and means for actuating said gathering devices, as and for the purpose set forth. 105
10. In a corn-harvesting machine, a frame, pivotally mounted at the rear end, and means for vertically adjusting the front end thereof, gathering-frames hinged to said first-mentioned frame at the front end thereof and extending forwardly therefrom in parallel relation, said gathering-frames slightly diverging 110 to a point adjacent to their front ends, and widely diverging at their front ends, gathering devices carried by said gathering-frames and extending to the point of wide divergence of said frames, and means for rocking said gathering-frames about their pivotal 115 support, as and for the purpose set forth. 120
11. In a corn-harvesting machine, pivotally-mounted gathering-frames extending in par-

allel relation, gathering devices carried by said frames, a driving-shaft for the gathering devices of each of said frames, one of said shafts forming a pivotal axis for one of said frames, and a universal joint interposed between the driving-shaft and the carrying-chains of the other of said frames, and means for rocking said frames about their pivots, as and for the purpose set forth.

10 12. In a corn-harvesting machine, the combination with ear-detaching devices, of a wiper arranged in advance of said ear-detaching devices, and means for actuating said wiper for clearing the throat or entrance to said ear-detaching devices, as and for the purpose set forth.

13. In a corn-harvesting machine, snapping-rolls and means for actuating the same, in combination with a wiper arranged at the 20 front end of said rolls, and means for actuating said wiper, as and for the purpose set forth.

14. In a corn-harvesting machine, the combination of snapping-rolls arranged parallel 25 to each other, said rolls being provided respectively with right and left corrugations adapted, when said rolls are rotated in opposite directions, to effect a feeding action upon the stalks of corn between such rolls from the 30 receiving toward the delivery ends thereof,

and spiral ribs formed on said rolls, the rib on each roll being arranged in reverse order with respect to, and of greater pitch than, the corrugations of such roll, the ribs on the respective rolls being arranged to coöperate 35 with each other to form angles with each other when said rolls are relatively rotated in opposite directions, the apex of the angle formed by those portions of such ribs which are on the upper surfaces of said rolls being presented toward the delivery ends of said rolls, as and for the purpose set forth.

15. In a corn-husking machine, spirally-corrugated snapping-rolls arranged parallel to each other, and means for rotating said rolls 45 in opposite directions, in combination with spiral ribs formed on said rolls, said ribs co-operating to form angles with each other, the apex of the angle formed by those portions of such ribs which are on the upper surfaces 50 of said rolls being presented toward the delivery ends of said rolls, as and for the purpose set forth.

In witness whereof I have hereunto set my hand, this 23d day of February, 1900, in the 55 presence of the subscribing witnesses.

AUGUST STEINER.
